MOTORIZED PENCIL POINTER

Clarence R. Taylor, Penfield, N. Y.

Application July 19, 1956, Serial No. 598,815

3 Claims. (Cl. 120—94)

This invention relates to a motorized pencil pointer. An object of the invention is to provide an efficient device for only "pointing" or sharpening the lead of pencils, and especially the mechanical type used by draftsmen, designers, artists, and the like.

Another object of the invention is to provide a device of good appearance that sits always ready for use within arm's length of a draftsman, so that when his pencil point becomes dull, he just has to reach out, lift the cover of the device, which lifting automatically starts the motor thereof, and point his pencil lead, wipe it on a convenient pad provided for that purpose, doing all of this with one hand, and quickly return to his work, stopping the operation of the device by merely closing the hinged cover which shuts off the motor.

A further object of the invention is to provide a novel device in which a moving or vibrating sand-paper or emery-paper pad or sheet is contained in a styled housing and operated by a standard electrical motor.

A still further object of the invention is to provide a device with a casing or housing which collects and retains pencil lead filings so that they cannot escape onto work sheets.

Another object of the invention is to provide efficient means in a motorized pencil pointer device for retaining an oscillating pad of sand-paper, whereby, when the pad has become worn, a new pad can be quickly substituted.

Still another object of this invention is to provide a lead filing collector and a pencil wiping pad in a motorized pencil pointer.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a top plan view taken substantially on line 1—1; Figure 2, and showing the housing in horizontal section.

Figure 2 is a side view of the device, the housing being shown in section.

Figure 3 is a transverse sectional view taken on line 3—3, Fig. 2, and looking in the direction of the arrows.

Figure 4 is a transverse, vertical sectional view taken substantially on line 4—4, Fig. 1, and looking in the direction of the arrows.

Figure 5 is a central, vertical sectional view taken on line 5—5, Fig. 1, and looking in the direction of the arrows.

Figure 6 is a fragmentary, sectional view showing the cover of the device in a raised position, and a pencil or the like as it appears when the point is being operated upon.

Figure 7 is a fragmentary sectional view taken on line 7—7, Fig. 6, and looking in the direction of the arrows.

Figure 8 is a perspective view of the retaining means for the steel pin.

Figure 9 is a transverse vertical sectional view taken on line 9—9, Figure 1, and looking in the direction of the arrows.

Figure 10 is a similar view to Figure 9, except that the lid or cover of the device is shown in a raised or open position.

2

Figure 11 is a perspective view of the upper face of the actuating plate, while

Figure 12 is a bottom view of this plate.

Figure 13 is a perspective view of the plate which is actuated by the eccentric pin of the motor shaft.

Figure 14 is an enlarged perspective view to illustrate the positioning of the eccentric pin on the rotor.

Figure 15 is a perspective view of the plate or unit having two abrasive surfaces of different qualities.

10 Referring to the drawings by numerals, 1 designates the housing or casing which may be made of any suitable material. Mounted on the casing 1 is a lid or cover 2. The casing rests on a projecting part 3, Fig. 5 of the base 4 with an upstanding part 5 of the base 4 projecting a distance up into the casing 1 as shown, which forms an admirable seal for preventing dust or foreign material resulting from the sharpening of the point from escaping from the casing.

Supported upon the base 4 is a flat metallic plate-like

20 frame 6 to which is assembled the motor winding 7. The casing 1 is provided with a notch, not shown, through which passes the electric cord, Fig. 1; this electric cord being attached by wire 9 to the motor and the other wire

10 of cord 8 is attached at 11 to the lower blade 12 of

25 the switch 13. Wire 14 is attached to the upper blade 15 of the switch 13. The two blades 12 and 15 are provided with contact lugs 16, whereby when they are in engagement the circuit is closed between the two blades 12 and 15. The closing of the circuit by the blades being made

30 to contact will start the motor 7, which motor is of any standard type, and with the motor operating the motor shaft 17 will be rotated, on which shaft 17 is the eccentric pin 18. This eccentric pin works in the aperture 19 of

35 plate 20, which plate slides between, in an oscillating manner, the guides 21, 21 on the bottom of actuating plate 22, Figs. 11 and 12. The plate 22 is provided with two vertical apertures 23 for the purpose hereinafter described. The plate 22 has an upstanding apron 24 and a depending apron 25.

40 The cover 2 has a substantially square portion 26, through which extends a pin 27 (Fig. 7), the ends of this pin being in enlarged portions 28 of the top of the casing 1. Depending from the top of the casing 1 is a suitable

45 bracket structure 29 in which is mounted a portion of flat spring 30. The flat spring 30 is held also by a lug 31 (Fig. 5) extending through the spring from the casing 1. The outer end of spring 30 bears upwardly against the squared portion 26 of the cover 2, whereby when the cover is raised as shown in Figure 6, the cover will be held in this open position by the action of spring 30.

When the cover is moved to a closed position, the flat spring 30 will engage the outer face of the enlarged portion 26 tending to hold the cover 2 in a closed position against accidental opening.

50

55 On the upper switch blade 15 is an upstanding lug 32 which is adapted to be pressed against when the cover 2 is raised to the position shown in Figure 10. Thus, the metal spring 30 will press against upstanding lug 32 causing the switch blades 12 and 15 to contact through their corresponding lugs 16, which will automatically start the motor (common structure not shown) which will rotate shaft 17 resulting in eccentric pin 18 in aperture 19 causing plate 20 to be reciprocated between the guides 21. The actuating plate 22 is mounted on studs

60 33 that are positioned in the apertures 23 of the plate 22. These studs 33 are fixed to the oscillating arms 34. The two oscillating arms 34 are fixedly secured to the top of rotatable post 35, Fig. 1. Each post 35 has a reduced portion 36, Fig. 3, the lower end of which rests

65 on the plate-like frame 6, and on the lower end of the post 35 is a second reduced portion 37 that extends into the base 38; there are two bases upon which the rotatable

posts 35 are mounted as shown in Figure 3. Each post 35 is provided with a coil spring 39. The upper end of each spring 39 is fastened at 40 to the post, while the lower end of the spring bears against a portion of the switch constituted by the blades 12 and 15. The springs 39 exert a torsional strain upon the posts 35.

The actuating plate 22 is placed upon the studs 33, Fig. 1, with the lower apron 25 extending outwardly as shown in Figure 6, whereby any filings from the pencil point will fall clear of the interior of the casing until the filings reach the bottom thereof where they may be collected until the operator cleans the casing 1. The formation of the casing at 3 and 5, Fig. 5, produces an admirable seal whereby the filings or loose substance cannot escape until the operator removes the same.

As hereinbefore indicated the device is placed on a desk or table convenient to the owner so that he can easily reach the cover 2, and upon raising the cover the closing of the circuit from the motor 7 will be caused, causing movement of the motor shaft 17 which will actuate the plate 20, causing it to reciprocate to a degree between the guides 21 resulting in the actuating plate moving in an oscillating manner for the purpose hereinafter described.

A combination sheet of sandpaper 41, Fig. 15, is employed, having a fine surface 42 and a coarse surface 43, and is placed upon plate 22 with studs 33 extending through the apertures 23a, holding the detachable sheet 4 securely upon the actuating plate. When the operator wishes to sharpen the point of the pencil or instrument he is using, the pencil point is placed first against the coarse portion 43 of the sheet 41, Fig. 6, and the point is sharpened by frictional contact, since the sheet is rapidly oscillating back and forth. Then when the operator wishes to finish the operation he can move the point to the fine portion 42 and secure the desired finished result. Then he can quickly lower the cover 2 which will cause the blades 12 and 15 to separate, stopping the motor.

The casing 1 is provided on each side with an open ended notch 44, Fig. 3. When the cover 1 is on the base, screws 45 are in these notches 44, holding the cover 1 securely in position.

A bracket 46, Fig. 2, is employed, on which is mounted a sponge 47, which sponge will permit the operator of the device to clean the point of the pencil or other instrument that has been sharpened.

It will be understood that pencil filings vibrate off the sandpaper plate or sheet both front and at sides of said sheet; the plate 22 has the apron 24 for preventing the filings falling over backward of the actuating plate, thereby preventing said filings from falling down into the base of the device; this is an important point since it is desirable to prevent undue soiling of the work sheet.

It is understood that the sandpaper sheet is replaceable, by simply lifting the same off the pins or studs 33 and inserting a new one. This can be done without removing the cover of the unit.

In Figures 6, 7 and 8 is shown the mounting and retaining means for the pivotal pin 27. As shown particularly in Figure 7, the central recess for the pin 27 is shown at 50. The inserts 51 are at the extreme outer ends of the pin 27. There is provided a central retaining member 52. It is to be understood that the inserts 51 are put in place and anchored to the lid 2 by means of liquid plastic cement.

The blades 12 and 15, Fig. 10, are mounted on spacers 13a and on screws 13b; the said spacers and screws are actually insulators. The long screws 13b serve the purpose of locking the motor stator 6 to the base boss 38.

On the base of the device there is placed a rubber pad 54 to keep the device from moving about on the surface upon which it is resting when the motor is running.

The built-in cord pull, as shown in Fig. 1, is essential from an Underwriter's laboratory viewpoint to guard

soldered joints against accidental strain. It is also to be noted that with the cover in place, it will be impossible to reach the contact plate with the standard Underwriter conical test probe.

It is to be understood that by using the springs 39 the dampening of the movement of arms 34 will prevent undue noise. Further, the spring structure shown in Figure 6 for the cover 2 will cause efficient spring action as the elements will move in a smooth manner for the best possible result.

While I have described the preferred embodiment of the invention and illustrated the same in the accompanying drawings, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In a device of the class described in combination, a casing, a motor in said casing, a drive shaft extending from said motor, an eccentric on the end of said drive shaft, an actuating plate, parallel guides on the bottom of said actuating plate, a slidable plate mounted for reciprocation between said parallel guides, said sliding plate having an aperture therein, said eccentric engaging in said aperture, a pair of pivotally mounted arms swingable in said casing, studs on the free ends of said arms connected to said actuating plate, and an abrasive sharpening sheet secured on the upper surface of said actuating plate.
2. In a device of the class described in combination, a casing, a motor in said casing, a drive shaft extending from said motor, an eccentric on the end of said driving shaft, an actuating plate, parallel guides on the bottom of said actuating plates, a slidable plate mounted for reciprocation between said parallel guides, said sliding plate having an aperture therein, said eccentric engaging in said aperture, a pair of pivotally mounted arms swingable in said casing, studs on the free ends of said arms connected to said actuating plate, an abrasive sharpening sheet secured on the upper surface of said actuating plate, a hinged cover for said casing above said sharpening sheet, and switch means operable by opening said cover for energizing said motor to reciprocate said sheet.
3. In a device for the class described in combination, a casing, a motor in said casing, a drive shaft extending from said motor, an eccentric on the end of said drive shaft, an actuating plate, parallel guides on the bottom of said actuating plate, a slidable plate mounted for reciprocation between said parallel guides, said sliding plate having an aperture therein, said eccentric engaging in said aperture, a pair of pivotally mounted arms swingable in said casing, studs on the free ends of said arms connected to said actuating plate, an abrasive sharpening sheet secured on the upper surface of said actuating plate, a hinged cover on said casing, said cover provided on its inner end with an enlarged portion, a two-bladed switch in said casing under said cover, means operated upon by the enlarged portion of said cover for closing the two-bladed switch only when said cover is in an open position, and means in said casing and connected to said motor shaft for electrically operating said shaft when said two-bladed switch is closed by the opening of said cover and said cover remaining in an open position.
